MECHANICAL STOKER

Adam B. Fahnestock, Manhasset, N. Y., assignor
to The Standard Stoker Company, Incorporated,
a corporation of Delaware

Application March 29, 1930, Serial No. 439,887

19 Claims. (Cl. 110—115)

My invention relates to stokers for locomotive or other boiler furnaces, and is more particularly concerned with mechanical stokers wherein a rotating disc is employed for projecting 5 the fuel over the furnace grate.

In stokers of this character provided in the past, the fuel is projected and distributed over the grate by a disc rotating at different rates of speed during successive periods, gradually increasing to a maximum and then gradually diminishing to a minimum; the disc then being rotated in the opposite direction through corresponding gradually increasing and gradually decreasing rates of speed, in order to spread fuel to both 10 sides of the fire. The disc of such stokers both projects and distributes the fuel over the fire, this together with the method of operation results in an overlapping of the fuel streams thrown to each side of the firebox causing a heavier fire 15 in the center of the firebox, and little if any fuel at all is delivered to the rear corners.

The efficiency of a boiler depends largely upon the amount of fuel fed per unit of grate area at equal intervals of time, and the uniform and even 20 distribution of this fuel over the entire grate. My present invention makes this delivery of the fuel possible and it is one of the principal objects of the invention.

This invention is an improvement upon the 25 structures of the past and another of its objects is the provision of an automatically operable, periodic reversing mechanism, whereby the fuel projecting disc is rotated at a constant speed and periodically reversed to project fuel uniformly and evenly first over one side of the grate 30 and then over the other.

A further object of my invention consists in the provision of a rotatable disc without the boiler furnace cooperating with a deflector extending 35 within the furnace, to spread the fuel evenly and in equal amounts over the entire grate.

A still further object of the invention is to provide in a stoker of the character specified a novel construction of fuel casing and associated 40 parts such that the fuel will be directed to a respective side of the firebox dependent upon the direction of rotation of the disc, at the same time preventing overlapping of the fuel streams to avoid formation of banks or thick spots in the 45 firebox.

My invention also contemplates and has for another one of its objects cooling those parts of the stoker that are exposed to the heat of the furnace by providing such a construction that 50 the rotary disc acts as a fan or pressure blower

to direct a cooling stream of air under the exposed parts; and further the disc blower functions to prevent fuel dirt from sifting in to the gearing of its operating mechanism, such dust being blown into the furnace beneath the main supply 5 of the fuel.

Somewhat more specifically a further object of this invention is to obtain the longest trajectory path for the fuel with a minimum speed of the rotating disc.

A still further object of my invention is the provision of a simple and novel mechanism for producing periodic reversal of the disc without materially changing its constant rate of speed.

Many advantages and additional objects of my 15 invention will be apparent from the following description and the drawings, in which

Fig. 1 is a central vertical longitudinal section of the stoker as applied to a locomotive;

Fig. 2 is an enlarged detail longitudinal section of a portion of the stoker;

Fig. 3 is a plan section on the line 3—3 of Fig. 2;

Fig. 4 is a detail vertical section on the line 4—4 of Fig. 3;

Fig. 5 is a plan section on the line 5—5 of Fig. 25 4, showing the driving mechanism;

Fig. 6 is a front elevation of the driving engine showing a part of the reversing mechanism;

Fig. 7 is an isometric view of the rotating disc 30 with a portion broken away; and

Fig. 8 is a detail section on the line 8—8 of Fig. 5.

The rear portion of a locomotive is indicated generally at 10, a portion of its tender at 11, its backhead at 12, its grate at 13, and the coupling connecting the locomotive and tender at 14.

The fuel transfer conduit comprises the usual tender trough 15, telescoping housing 16, and screws 17 and 18 disposed therein, connected at their adjacent ends by universal joints of conventional form as illustrated. Carried at the forward end of the trough 15 is a crusher 19 which is adapted to engage the coal which has been moved forward by the screw 17. The forward portion of the telescoping housing 16 communicates with the forwardly and upwardly curved

casing 20, by means of an elbow 21 universally connected at its rearward end to the housing 16 and rigidly connected at its forward end to the casing 20 by suitable means. To the casing 20 is attached the casing 22, said casing 22 as best shown in Fig. 3 having fastened thereto the driving engine 23 on one side and the reversing mechanism 24 on the other side. Extending 45 within both the casing 22 and the forwardly 50

55 the rotary disc acts as a fan or pressure blower

curved casing 20 is located a disc 25 provided on its upper face or fuel supporting surface with the ribs or projections 26. It will be observed that the fuel supporting surface of said disc is 5 slightly below the floor of the feed casing 20, but forms, in effect, a forward continuation thereof. The casing 20 has an opening at its forward end communicating with the firing opening 27 through which the fuel is fed, and is open at 10 its rearward end for receiving fuel from the conveyor. Both the forward curved portion 20 and the casing 22 are secured through the flanges 28, 28a and 29 respectively, to filler plate 30, which in turn is fastened to the backhead 12 of 15 the locomotive.

The sidewalls of the casing 20 taper inwardly from the center line of the disc 25 forward, as is best illustrated in Fig. 3. In constructions not having tapering sidewalls and in which firing 20 is done by periodic reversal of a disc, a fan shaped bank of fuel is formed in the firebox extending forwardly from the backhead, since the area covered by the bank receives a double supply of fuel. It was noted that a great amount of fuel seemed to follow along the sidewall of the casing, this fuel being that which could easily get out of 25 reach of ribs or vanes provided on the disc, being thrown against the sidewalls of the casing at a point approximately in line with the center line 30 of the disc parallel to the backhead and forming the above described bank. To restrain the fuel and hold it longer in contact with the propelling ribs 26, the casing is drawn in at the sides from the center line of the disc forward. This construction almost entirely eliminates the above described fan shaped bank of fuel in the firebox, and prevents overlapping of fuel along the center line of the firebox. By clockwise rotation of the disc 25 the right half of the box may be fired, 35 and the left half of the box by counter-clockwise rotation.

The disc 25 comprises a hub portion 31 which is bored out to receive an upright shaft 32 supported on radial and thrust bearings 33 and 34. 40 The shaft 32 is preferably inclined so that the disc is tilted at an angle of eight degrees from the horizontal, since at this inclination it is possible to obtain the longest trajectory path for the fuel with a minimum speed of the rotating disc. 45 While eight degrees is the preferred inclination it will be understood that the inclination may be more or less than eight degrees if desired. Also if desired, the disc may be mounted horizontally without departing from the spirit of my invention.

The ribs or projections 26 on the disc 25 may be of any shape but are shown in the drawings with curved faces which flare outwardly from the hub to the peripheral portion of the disc 25. The 50 ribs may be cored out as shown in Figures 1 to 3 in order to reduce their weight. The underside of the disc 25 is provided with ribs 35. The casing 22 is so designed as to provide the space 36 under and around disc 25 and the opening 37 55 at the rear of and near the center of the casing. The space 36 enlarges in width toward the front and in combination with the ribs 35 becomes a pressure blower. Air entering the opening 37 is thrown out through the openings 38 around the 60 disc 25 and the opening 39 at the front of the stoker, whence it passes under the deflector plate 40 to the firebox. This flow of air sweeps the coal dust into the firebox and thus prevents it from sifting into the gears and bearings of the 65 gear box. The current of air passing under the

deflector 40 constitutes a cooling medium for the deflector and other parts of the stoker which are exposed to the heat of the firebox. The current of air entering the firebox assists in the complete combustion of the fuel.

The deflector plate 40 is of novel construction and designed to permit the fuel reaching the back corners of the firebox and also to prevent the accumulation of fuel at the corners of the firedoor opening. The plate 40 extends rearwardly into the casing 20 and fits closely about the disc 25, and forwardly slightly within the firebox. The extensions 41 and 41a are provided to act as extensions to the sides of the casing 20. The extensions 41 and 41a prevent the accumulation 10 of fuel at the corners of the firedoor opening and exert a directive influence on the projected fuel. Deflector plate 40 is supported from the backhead 12 by the depending portions 42. The deflector plate 40 is provided with a pair of grooves 15 20 25 30 35 40 43 and 44 having their front walls curved forwardly and laterally for directing a certain amount of the fuel laterally into the back corners of the firebox, these curved walls being raised slightly above the plane of the plate to constitute the ribs 45 and 46 which act to intercept a portion of the fuel being delivered into the firebox, and directing the portion intercepted to the rear of the firebox.

The disc 25 is driven by the engine 23. The drive mechanism as best shown in Fig. 5 is self explanatory and requires no detailed description. The drive shaft is indicated at 47 and communicates through suitable reduction gearing with the intermediate shaft 48 which in turn operates the disc shaft 32 through the engaged gears 49 and 50. The drive shaft 47 and the intermediate shaft 48 are supported on suitable bearings. The shaft 32 carries the gear 50 which is comprised in means for rotating the disc 25 first in one 40 direction and then in the opposite direction.

Referring now particularly to Fig. 4 and Fig. 5; the reversing mechanism comprises the casing 51 enclosing a shaft 52. The shaft 52 is operated from the intermediate shaft 48 through the worm 53 mounted on the intermediate shaft 48 45 which engages the worm gear 54 mounted on the shaft 52. The disc and reversing mechanism are operated from the same shaft in timed relation with each other. The gear shaft 52 projects upward and the upper or lead portion 55 is threaded and carries the nut 56. The movement of the nut 56 along the threaded shaft 55 in turn moves the shaft 57 by means of the forked arm member 58. The forked ends of the arm 58 are fastened 50 to the nut 56 while the opposite end communicates with the shaft 57. The shaft 57 is connected to a toggle switch if the drive is electric or to a toggle reverse mechanism shown in Figures 5 and 6. The direction in which the disc 25 rotates may be reversed at any predetermined uniform intervals of time by the proper selection of reduction in gearing and the number of threads on shaft 55. Reversal of the disc approximately every two minutes has been found to 60 be desirable, but it will be obvious that the time interval between reversals may be varied greatly and still be operative and produce good results.

Referring to Figures 5, 6 and 8; 59 is an arm fixedly connected at one end to the shaft 57; 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

key 64. Pressure is exerted on the key 64 through the coiled spring 65. The movement of the nut 56 along the threaded shaft 55 moves the shaft 57 through the arm 58. The shaft 57 in turn 5 raises the arm 59 increasing the tension on the spring 62 until it overcomes the pressure exerted on the key 64, through the spring 65. The tension on the spring 62 causes the arm 60 to jump and assume the position shown in broken lines in 10 Figure 6, and thereby moves the shaft 61 and forces the key 64 out of engagement with the slot 63 in said shaft. Immediately after the arms 59 and 60 have assumed the new position, the tension on the spring 62 is released and the key 15 64 which was forced from one of the slots 63 is forced into the other slot by the pressure of the spring causing reversal of the steam admission port in the engine. The slot and key arrangement described prohibits any rotary movement 20 of the shaft 61, which would affect the operation of the motor 33, until the arm 59 has reached its maximum reversing position. Tension on the spring 62 then will be sufficient to overcome the action of the spring 65 in restricting rotation of 25 the shaft 61. When the shaft 61 moves it is quickly pulled to the end of its travel by the spring 62 and the key 64 will then engage the other slot 63. The movement of the arm 60 from the position shown in full lines to the position 30 shown in broken lines, Fig. 6, and vice versa is rapid and almost instantaneous, and after reversal of the disc in the direction of rotation the maximum speed is quickly restored. Reversal in the direction of rotation of the disc 25 takes 35 place almost instantaneously and there is no appreciable slowing up of the disc before reversing and no appreciable acceleration after reversal.

In operation, coal which enters the trough 15 from the bin 11 is carried forward by rotation of 40 the screw 17 into the telescoping housing 16 from where it is carried forward by rotation of the screw 18. The coal is urged forwardly and upwardly through the rearward end of the casing 20 onto the rotatable disc 25. With the disc rotating in clockwise direction fuel is fed to the right half of the firebox and counter-clockwise to the left half, and by reason of the tapering sidewalls of the casing 20 no overlapping of fuel takes place along the center line of the firebox. 45 A part of the fuel projected forwardly from the disc 25 is intercepted on the deflector plate 40 and the novel construction of the plate 40 permits of fuel to reach the rear corner of the firebox on the respective side toward which the disc 50 is rotating.

I claim:

1. In a stoker, in combination, a firebox, a fuel delivery casing operatively associated therewith, a rotatable fuel projecting disc mounted in the floor of said casing for propelling fuel forwardly therefrom into said firebox, the fuel supporting surface of said disc forming an approximate continuation of said floor, and means for delivering fuel forwardly into said casing through the rear end thereof in a plane substantially parallel to the fuel supporting surface of said disc to that portion of said disc remote from the firebox.
2. In a stoker, in combination, a firebox having a firing opening in its backwall, a fuel delivery casing operatively associated therewith and at its forward end communicating with said firing opening, a rotatable fuel projecting disc mounted on an upstanding axis in the floor of said casing for propelling fuel forwardly through 70 said firing opening in a plane substantially per-

pendicular to said axis, the fuel supporting surface of said disc forming an approximate continuation of said floor, and a conveyor delivering fuel forwardly into said casing through the rear end thereof, said casing and disc being arranged 5 so that the fuel is delivered continuously to said disc in the plane of the path of its rotation.

3. In a stoker, in combination, a firebox having a firing opening in its backwall, a fuel delivery casing outside of said firebox and operatively associated therewith, said casing open at its forward end to communicate with said firing opening, a rotatable fuel projecting disc mounted on an upstanding axis in the floor of said casing for propelling fuel forwardly through said firing 10 opening in a plane substantially perpendicular to said axis, the fuel supporting surface of said disc forming an approximate continuation of said floor, a conveyor delivering fuel forwardly through the rear end of said casing to that portion of said disc remote from the firing opening, and deflecting means within the firebox arranged to intercept a portion only of the propelled fuel directing the intercepted portion to the rear corners of said 15 firebox to assist said disc in uniformly distributing the fuel.

4. In a device of the class described, a fuel casing having top, bottom, and sidewalls, said casing being provided with an open forward end and an opening in its rear end through which 20 fuel is delivered forwardly to said casing, and a rotatable disc mounted in the casing floor and arranged therewith to receive fuel continuously from said opening in the rear end in the plane 25 of the path of the rotation of said disc and project it through said open forward end of the casing, the fuel supporting surface of said disc forming an approximate continuation of said floor, the opening in the forward end of said casing being of less width than the diameter of 30 said disc.

5. In combination, a firebox, a fuel delivery casing operatively associated with said firebox, means for continuously supplying fuel forwardly to said casing through the rear end thereof, a rotatable disc in said casing arranged to receive a continuous supply of fuel on that portion of its surface remote from the firebox and periodically distributing the fuel to each side of the firebox, 45 and means for rotating said disc first in one direction and then in the opposite direction at a constant speed for a predetermined period of 50 time.

6. In combination, a firebox, a fuel delivery casing operatively associated with said firebox, 55 means for supplying fuel forwardly to said casing through the rear end thereof, means including a rotatable disc in said casing receiving the fuel on that portion of its surface remote from the firebox and periodically projecting the fuel 60 to each side of the firebox, and a deflecting means within the firebox acting to direct a portion of the propelled fuel to the rear corner of the firebox on the side to which the fuel is being delivered.

7. In combination, a firebox, a fuel delivery 65 casing operatively associated with said firebox, means for continuously supplying fuel forwardly to said casing through the rear end thereof, means including a rotatable disc in said casing arranged to receive a continuous supply of fuel 70 forwardly through said rear end in a plane substantially parallel to the fuel supporting surface of said disc and periodically distributing the fuel to each side of the firebox and deflecting means within the firebox acting to direct a portion of 75

the propelled fuel to the rear corner of the firebox on the side to which the fuel is being delivered.

8. In combination, a firebox having a firing opening in the end wall thereof, a fuel casing opening into said firing opening, a rotatable disc mounted in said casing, means for periodically rotating said disc in opposite directions for timed intervals, a conveyor for delivering fuel forward-

10 ly onto said disc through the rear end of said casing in a plane substantially parallel to the fuel supporting surface of said disc, said disc periodically projecting the fuel to each side of the firebox, and deflecting means within the firebox acting to direct a portion of the propelled fuel to the rear corner of the firebox on the side to which the fuel is being delivered.

9. In a stoker, in combination, a firebox having a firing opening therein, a fuel delivery casing 20 in communication with said firing opening, a rotatable fuel projecting disc inclined forwardly and upwardly toward said opening and mounted in the floor of said casing for propelling fuel forwardly therefrom into said firebox, and means

25 for delivering fuel forwardly into said casing through the rear end thereof to the portion of said disc remote from the firebox.

10. In a stoker, in combination, a firebox having a firing opening in the end wall thereof, a fuel casing opening into said firing opening, a rotatable fuel projecting disc inclined forwardly and upwardly toward said opening and mounted in the floor of said casing for projecting fuel forwardly therefrom into said firebox, the fuel 30 supporting surface of said disc forming an approximate continuation of said floor, means for delivering fuel forwardly to said casing through the rear end thereof in a plane substantially parallel to the fuel supporting surface of said disc, and deflecting means extending into the firebox forwardly from said disc.

11. In a mechanical stoker, the combination of a fuel casing having converging sidewalls, a 45 rotatable disc mounted in the floor of said casing and arranged to receive fuel in a plane substantially parallel to the fuel supporting surface of said disc, said fuel supporting surface forming an approximate continuation of said floor, a deflector plate in communication with said fuel casing and arranged to receive fuel therefrom, said deflector plate having its rearward edge following the contour of said disc, and means disposed at the forward end of said deflector plate for intercepting a portion of the fuel and deflecting it laterally.

12. In a mechanical stoker, the combination of a fuel casing having converging sidewalls, and an opening in its rear end for delivering fuel, a rotatable disc mounted in the floor of said casing 60 and arranged to receive fuel forwardly from said opening in a plane substantially parallel to the fuel supporting surface of said disc, said fuel supporting surface forming an approximate continuation of said floor, a deflector plate in communication with an opening in the forward end of said casing for receiving fuel therefrom and means disposed at the forward end of said deflector plate for intercepting a portion of the fuel and deflecting it laterally.

13. In a mechanical stoker, the combination of a fuel casing having converging sidewalls, a rotatable disc mounted in the floor of said casing and arranged to receive fuel in a plane substantially parallel to the fuel supporting surface of said disc, said fuel supporting surface forming

an approximate continuation of said floor, and a deflector plate so arranged that the sidewalls of said casing form retaining sidewalls for the rearward portion of said deflector plate, shoulders on said deflector plate constituting extensions of the casing walls, grooves disposed in the forward end of said deflector plate curving forwardly and laterally and ribs carried on said plate and forming walls for said grooves.

14. In combination with a firebox having a 10 firing opening in a wall thereof, a mechanical stoker comprising a casing in communication with said firebox through the firing opening thereof, a fuel projecting disc rotatably mounted in said casing to rotate about an upstanding 15 axis, the underside of said disc together with said casing forming a chamber which communicates with said firing opening at its forward end and with the atmosphere at its rearward end, the underside of said disc being in the form of 20 a blower fan arranged to discharge the current of air entering the rearward end of said chamber through the forward end thereof into the firebox.

15. In combination with a firebox having a 25 firing opening in a wall thereof, a mechanical stoker comprising a casing in communication with said firebox through the firing opening thereof, a fuel projecting disc rotatably mounted in said casing to rotate about an upstanding 30 axis, drive mechanism for rotating said disc disposed beneath the fuel supporting surface of said disc, the under side of said disc together with said casing forming a chamber which communicates with said firing opening at its forward end and 35 with the atmosphere at its rearward end, and fan blades secured to said disc intermediate the under side of said disc and said drive mechanism, said fan blades arranged to discharge the current of air entering the rearward end of said 40 chamber through the forward end thereof into the firebox.

16. In combination with a firebox having a firing opening in a wall thereof, a mechanical stoker comprising a fuel deflector plate extending into the firebox through said opening, a casing, a fuel projecting disc rotatably mounted in said casing to rotate about an upstanding axis, said casing having a floor forming with the underside of said disc a chamber in communication 50 with said firing opening at its forward end and with the atmosphere at its rearward end, the underside of said disc being in the form of a blower fan arranged to discharge the current of air entering the rearward end of said chamber 55 through the forward end thereof into the firebox, such current of air impinging the underside of said fuel deflector plate.

17. In a mechanical stoker, the combination of a rotary disc for projecting fuel, means for conveying fuel to said disc, and mechanism for alternately rotating the disc in one direction for a predetermined period and then in the opposite direction for a predetermined period, said mechanism being constructed to actuate the disc for 60 a plurality of revolutions during each period including a plurality of successive revolutions of the disc for the greater portion of each period at the same speed.

18. In a mechanical stoker, the combination 70 of a rotary disc for projecting fuel, a casing enclosing said disc open at one end for delivery of fuel to said disc and open at the opposite end for the discharge of fuel therefrom by said disc, fuel deflecting means adjacent the discharge end of 75

the casing positioned in the path of the projected fuel, and mechanism for alternately rotating the disc in one direction for a predetermined period and then in the opposite direction for a predetermined period, said mechanism being constructed to actuate the disc for a plurality of revolutions during each period including a plurality of successive revolutions of the disc for the greater portion of each period at the same speed.

5 19. In combination with a firebox having a firing opening, a casing having an opening at one end in communication with said firing opening, a rotary fuel projecting disc mounted in said

casing for projecting fuel therefrom through said firing opening, fuel deflecting means adjacent the firing opening positioned in the path of the projected fuel, and mechanism for alternately rotating the disc in one direction for a predetermined period and then in the opposite direction for a predetermined period, said mechanism being constructed to actuate the disc for a plurality of revolutions during each period including a plurality of successive revolutions of the disc for the greater portion of each period at the same speed.
